UNITED STATES PATENT OFFICE.

WALTER H. SMITH, OF NILES, OHIO, ASSIGNOR TO THE HARRIS AUTOMATIC PRESS COMPANY,
OF NILES, OHIO, A CORPORATION OF OHIO.

PRINTING-PRESS.

No. 920,406.

Specification of Letters Patent.

Patented May 4, 1909.

Application filed May 14, 1908. Serial No. 432,872.

To all whom it may concern:

Be it known that I, WALTER H. SMITH, of Niles, in the county of Trumbull and State of Ohio, have invented certain new and useful 5 Improvements in Printing-Presses; and I do hereby declare the following to be a full, clear, and exact description of the invention, such as will enable others skilled in the art to which it appertains to make and use the 10 same.

The primary object of this invention is to provide improved throw-off mechanism for printing presses capable of being automatically actuated in the event of any interruption 15 in the feed-supply; and a further object is to provide improved means for actuating the prime mover of stop mechanism.

The invention will be hereinafter fully set forth and particularly pointed out in the 20 claims.

In the accompanying drawings, Figure 1 is a front elevation, with parts broken away. Fig. 2 is a side elevation. Fig. 3 is a detail.

Referring to the drawings, 1 designates the 25 form cylinder of a printing press, (or it may be the transfer cylinder of a planographic press) and 2 the impression cylinder mounted at its ends in eccentric bearings 3, after the manner suggested by Letters Patent of the 30 United States No. 577,405; of February 16, 1897. According to the means shown in that patent the throw-off mechanism for the 35 press cylinder comprised a spring-impelled shaft to which the eccentric bearings were connected; such shaft being normally held by a trip which was caused to release the spring-impelled shaft upon any interruption in the feed supply.

In the present instance, instead of employing a spring-impelled shaft for shifting the eccentric bearings, to each of the latter I pivotally connect a link 4 to which in turn is connected a second link 5, both links 5 being pivoted on a shaft 6 having its bearings in press frame 7 and extending across the machine. The two links, 4 and 5, form a toggle so that when they are in their extended positions, with the center of the connecting pin 8 slightly below or in line with the centers of the two end 50 pivots, the impression cylinder will be in its operative position relative to the form cylinder. Hence, in order to throw-off the cylinder it is necessary to break joint between the two links constituting the toggle. This may be

accomplished manually by depressing a handle 9 on shaft 6.

In order to actuate the toggles automatically, in the event of any interruption in the feed supply, I preferably employ trip mechanism of the character shown in the drawings, but inasmuch as this forms the subject of a concurrent application for patent, Serial No. 433,974, filed May 20, 1908, it will be but briefly described herein. This trip mechanism embodies a constantly-actuated shaft 10 whereon is mounted a collar carrying a feeler lever 12, a tooth of which will, in the event of any interruption in the feed supply, enter a cut-out or notch in a disk 13 on a tubular shaft 14 mounted on shaft 10. The tubular 70 shaft 14 carries at one end a second disk 15 from which projects a lug 16 which normally stands in close proximity to the upwardly extending arm of a bell-crank lever 17, which latter is connected by a link 18 to the toggle 75 link 5. The tubular shaft 14, and its disk 15, are normally idle. When it is interlocked with shaft 1, the lug 16 by engaging bell-crank-lever 17 will turn the latter, and through link 18 the toggle will be broken to 80 automatically throw-off the press cylinder. In actuating the throw-off, stop mechanism may also be actuated to throw the press out of operation. For this purpose a vertically-disposed rod 19 is connected at its upper end 85 to link 5, and at its lower end to an arm 22 of a rock shaft 23 carrying a latch 24 which, when the press is in operation, engages and holds a spring-impelled prime mover 25 which is shown in the form of a clutch controlling yoke to which is attached a handle 27 to enable the machine to be started by pressing the handle downwardly. This places under tension the spring of the prime mover and enables the latter to be held by 90 latch 24. It is not possible for the yoke to remain or stay locked in running position unless the impression is on, as the latch 24 cannot be moved to lock the yoke without throwing on the impression by restoring the 100 toggles. It follows, therefore, that upon the breaking of the toggles, whether it be by manual pressure on handle 9, or automatically by the turning of bell-crank-lever 17, the prime mover of the stop mechanism will 105 be thrown into releasing position.

I claim as my invention—
1. In a printing press having a rotary

- 20 cylinder, and eccentric bearings therefor, means for holding said cylinder in its normal position, such means comprising a toggle connected to each bearing, in combination with a lever connected to one of the toggle links at a point between the pivots thereof, and trip mechanism for actuating said lever to break said toggles in the event of any interruption in the feed supply.
- 10 2. In a printing press having a rotary cylinder, and eccentric bearings therefor, means for holding said cylinder in its normal position, such means comprising a toggle connected to each bearing, in combination with a lever connected to one of the toggle links, trip mechanism for actuating said lever to break said toggles in the event of any interruption in the feed supply, such trip mechanism comprising a normally idle shaft having means for engaging and turning said lever, a second shaft, and a feeler lever carried by said second shaft for actuating the first mentioned shaft in the event of any interruption in the feed supply.
- 15 3. In a printing press having a rotary cylinder, and eccentric bearings therefor, means for holding said cylinder in its normal position, such means comprising a toggle connected to each bearing, in combination with a lever connected to each bearing, in combination with a lever connected to one of the toggle links, trip mechanism for actuating said lever to break said toggles in the event of any interruption in the feed supply, such
- 20 trip mechanism comprising an operating shaft, a feeler lever carried thereby, a second shaft designed to be actuated by said feeler lever in the event of any interruption in the

feed supply, and a disk carried by said second shaft having a pin for engaging the lever connected to the toggle. 40

4. In a printing press, in combination, stop mechanism, a prime mover therefor, a latch for holding such prime mover, eccentric bearings for one of the press cylinders, means for holding such cylinder in its normal position, such means comprising a toggle connected to each bearing, means connected to one of the toggle links for breaking the toggles in the event of any interruption in the feed supply, and means connecting one of the toggles to said latch, whereby when the press cylinder is thrown off the prime mover will be released. 45

5. In a printing press, in combination, stop mechanism, a prime mover therefor, a latch for holding such prime mover, eccentric bearings for one of the press cylinders, means for holding such cylinder in its normal position, such means comprising a toggle connected to each bearing, means connecting the two toggles, a lever connected to one toggle, means for actuating such lever to break the toggles in the event of any interruption in the feed supply, and means connecting one of the toggles to said latch, whereby when the press cylinder is thrown off the prime mover will be released. 50

In testimony whereof, I have signed this specification in the presence of two subscribing witnesses. 70
